UNITED STATES PATENT OFFICE.

JAMES F. RICHARDS, OF ALLIANCE, NEBRASKA.

AUTOMATIC SLACK-ADJUSTING DEVICE.

1,087,182.

Specification of Letters Patent. Patented Feb. 17, 1914.

Application filed March 26, 1913. Serial No. 757,003.

To all whom it may concern:

Be it known that I, JAMES F. RICHARDS, a citizen of the United States, residing at Alliance, in the county of Boxbutte and State of Nebraska, have invented a new and useful Automatic Slack-Adjusting Device; and I do hereby declare the following to be a full, clear, and exact description of the invention, such as will enable others skilled in the art to which it appertains to make and use the same.

This invention relates to a new and useful chafing iron or mechanism, for absorbing the slack between the engine and the coal tender.

15 It is the principal object of the invention to take up automatically the slack, occasioned by the wear and tear of the coupling pin and draw bar of the locomotive and tender.

20 The invention comprises further features and combination of parts, as hereinafter set forth, shown in the drawings and claimed.

In the drawings:—Figure 1 is a view in elevation showing portions of a locomotive and a coal tender, illustrating the application of the improved slack adjuster or chafing iron. Fig. 2 is a sectional view longitudinally through the slack adjuster. Fig. 3 is a sectional view on line 3—3 of Fig. 2. Fig. 30 4 is a transverse sectional view on line 4—4 of Fig. 2. Fig. 5 is a detail perspective view of the upper chafing iron of the slack adjuster. Fig. 6 is a detail perspective view of the wedge-shaped sliding chafing iron.

35 Referring to the drawings 1 designates a portion of the locomotive or engine, while 2 denotes a portion of the coal tender, the two being connected in the usual manner by a conventional form of pin and draw bar (not particularly shown). Secured to the coal tender is a cylinder 3, into which air is forced through the pipe 4, from any suitable source (not shown), in order to actuate the piston 5, between which and the end 6 of the cylinder a spring 7 is interposed. This spring 7 is designed to hold the piston 5 normally in the position shown in Fig. 2. The piston 5 is carried upon one end of the piston rod 8. The piston rod 8 as at 9, 40 is pivoted to the lug 13 of the wedge-shaped sliding chafing iron 14, which is received in the rear chafing iron 15.

The rear chafing iron 15 is provided with L-shaped flanges 16, which are received by the grooves 17 of the sliding chafing iron. The side portions of the sliding chafing iron

14 are provided with ratchet teeth 18, which are engaged by the spring tensioned pawls 19, which are pivoted at 20, to the side of the rear chafing iron 15. The ends 21 of the spring tensioned pawls enter the openings 22 of the rear chafing iron, in order to engage the said teeth 18.

Journalized on pins 23, which are mounted in the recesses 24 of the sliding chafing iron, and in the recesses 25 are rollers 26, which are designed to engage the inclined surface 27 of the rear chafing iron, when the sliding chafing iron is received between the flanges 16 of the rear chafing iron. The rear chafing iron 15 is carried by and is secured to the coal tender 2 as at 28.

When the sliding chafing iron enters between the flanges 16 sufficiently, it will frictionally contact with the convexed rub block 29, which is mounted upon the engine, shown clearly in Figs. 1 and 2.

When a locomotive and coal tender are equipped with this improved slack adjuster, and the parts adjusted as shown in Fig. 1 of the drawings, and it is desired to absorb or take up the slack, occasioned by the wear and tear upon the pin and draw bar (not shown), air is admitted through the pipe 4 into the cylinder 3, which will force the piston 5 in the direction of the arrow *a* in Fig. 2, against the action of the spring 7. This will cause the sliding chafing iron 14 to further enter between the flanges 16 of the rear chafing iron 15. The spring tensioned pawls or levers 19 will then engage the teeth 18, and lock the sliding chafing iron in place, thereby taking up or absorbing the slack or lost motion between the pin and the draw bar (not shown). The rollers 26 constitute anti-frictional means between the sliding chafing iron and the rear chafing iron 15. In order to disconnect or remove the sliding chafing iron, the pawls or levers 19 may be disengaged from the teeth, and after the pin and draw bar (not particularly shown), have been disconnected, the sliding chafing iron may be withdrawn, by cutting off the air from the cylinder 3, which will permit the spring to return the piston 5 to its normal position, as shown in Fig. 2. The rub block 29 and the under surface of the sliding chafing iron 14 and all the other parts, which slidably engage the sliding chafing iron and the rear chafing iron, are to be well lubricated.

From the foregoing it will be noted that

there has been devised a novel and efficient slack adjuster or absorber, for taking up the slack between the pin and draw bar, and one which has been found practical and 5 desirable.

The invention having been set forth, what is claimed as new and useful is:—

In combination, a chafing iron adapted to be secured to one car and having laterally 10 extending guide flanges extending toward one another and provided with spring-tensioned levers, a wedge-shaped chafing iron having guide grooves to receive the flanges of the first chafing iron and provided with 15 teeth to be engaged by the spring-tensioned lever, one face of the wedge-shaped chafing iron having recesses, anti-frictional rollers

detachably journaled in said recesses and adapted to engage one face of the first chafing iron between the flanges, a rub block 20 adapted to be supported by a second car and arranged adjacent the sliding wedge-shaped chafing iron for engagement thereby, and means having connections with the sliding chafing iron and pneumatically actuated for 25 forcing the wedge-shaped chafing iron between the flanges.

In testimony whereof I have signed my name to this specification in the presence of two subscribing witnesses.

JAMES F. RICHARDS.
